(57) **CLAIM**

The ornamental design for a cushion for patient interface, as shown and described.

DESCRIPTION

FIG. 1 is a front perspective view of a cushion for a patient interface according to a first embodiment of our design;

FIG. 2 is a reverse perspective view thereof;

FIG. 3 is a front view thereof;

FIG. 4 is a rear view thereof;

FIG. 5 is a top view thereof;

FIG. 6 is a bottom view thereof;

FIG. 7 is a left side view thereof;

FIG. 8 is a right side view thereof;

FIG. 9 is a front perspective view of a cushion for a patient interface according to a second embodiment of our design;

FIG. 10 is a reverse perspective view thereof;

FIG. 11 is a front view thereof;

FIG. 12 is a rear view thereof;

FIG. 13 is a top view thereof;

FIG. 14 is a bottom view thereof;

FIG. 15 is a left side view thereof; and,

FIG. 16 is a right side view thereof.

Where included, the use of stippling is provided to show contrast in materials to differentiate between different areas of the design.

FIGS. 1–16 use stippling which is not part of the claimed design.

1 Claim, 8 Drawing Sheets
